UNITED STATES PATENT OFFICE.

JOSEPH H. DONAT, OF NEW YORK, N. Y., ASSIGNOR TO GILLIS & GEOGHEGAN, OF NEW YORK, N. Y., A FIRM.

HOISTING MECHANISM.

1,333,064.

Specification of Letters Patent.

Patented Mar. 9, 1920.

Application filed August 2, 1919. Serial No. 314,857.

To all whom it may concern:

Be it known that I, JOSEPH H. DONAT, a citizen of the United States, residing in the city of New York, borough and county 5 of Queens, in the State of New York, have invented a certain new and useful Improvement in Hoisting Mechanism, of which the following is a specification.

The invention relates to power driven 10 machinery for hoisting loads, and more particularly to electrically operated ash-hoists designed to raise ash-cans and like loads, from a cellar to the sidewalk.

The object of the invention is to provide 15 simple, easily operated means for raising the load by an electric motor, and for stopping such motor during the lowering operation, by gravity, and controlling such lowering by a brake, thus effecting an economy 20 in current and permitting the empty cans or other load to be lowered rapidly and checked quickly. Another important object 25 is to provide means for automatically limiting the length of cable wound upon the hoisting-drum in the hoisting operation and thus preventing overwinding, and a further object is to provide means whereby the hoisting, lowering and braking operations 30 are all controlled by a single lever.

The invention consists in certain novel 35 features and details of construction and arrangement by which the above and other objects are attained, to be hereinafter described and claimed.

The accompanying drawings form a part 40 of this specification and show an approved form of the invention.

Figure 1 is a side elevation of a hoisting head embodying the invention.

Fig. 2 is a corresponding plan view, with 45 certain portions broken away to show contained parts.

Fig. 3 is a vertical transverse section 50 through the hoisting drum and brake drum, taken on the line 3-3 in Fig. 1.

Fig. 4 is a side view of a portion of the differential gear, the hoisting-shaft being shown in cross-section.

Similar letters of reference indicate the 55 same parts in all the figures.

A is a bifurcated frame with its arms A¹ extended horizontally forward, shown as supported in the upper end of a standard A² which may be understood to be received

telescopically in a hollow post, not shown, 55 set in a hoistway extending from the cellar to the sidewalk.

Mounted on and above the frame is an electric motor B of any approved type, controlled by any suitable switch device, not 60 shown, contained in the controller casing A³, on a controlling shaft C, mounted transversely in the arms A¹ and free to oscillate.

The drive shaft B¹ of the motor extends 65 longitudinally of the frame and is equipped with a brake-drum B² and carries at its outer or forward end a worm B³.

Inclosing the motor brake-drum B² are 70 two jaws D held in frictional contact with the drum by a spring, and separated to free the drum by a cam D¹ between the lower ends of the jaws, shown in dotted lines in Figs. 1 and 2, mounted on a short longitudinally extended shaft D². This motor 75 brake is preferably of the usual well-known construction.

At the forward ends of the arms A¹ is a transverse hoisting shaft F having keyed 80 thereon adjacent one of the arms, the winding drum F¹ and a beveled gear-wheel F²; a similar gear-wheel F³ is fixed on a sleeve F⁴ loosely inclosing the opposite end of the shaft F, and on the sleeve F⁴ is keyed a 85 hoisting brake-drum F⁵. An annular worm-wheel G encircles the space between the beveled gear-wheels F² F³ and receives the outer 90 ends of the spider arms H¹, see Figs. 3 and 4, of a spider-frame H the hub of which is loosely mounted on the shaft F between the wheels F² F³. The spider arms H¹ each carries a beveled pinion H² in mesh with both the beveled gear-wheels F² F³, and the teeth of the worm-wheel G mesh with the worm 95 B³. The beveled gear-wheels F² F³ with the beveled pinions H² and worm-annulus G form a differential gear, and operate in the manner usual in such mechanism.

On the controlling shaft C is a beveled pinion C¹, indicated in dotted lines in Figs. 1 and 2, in mesh with a similar pinion D³ 100 on the short shaft D², the arrangement being such as to permit the jaws D to clamp the motor brake-drum B² and hold the motor shaft B¹ when the switch, not shown, on the controlling shaft C is thrown, by turning 105 the latter, to interrupt the current.

On an overhung end of the shaft C is the controlling lever E by which the shaft

may be oscillated, and the boss E¹ of the lever carries an upwardly presented beveled-faced lug or spur E². On the opposite end of the controlling shaft C, within the arm 5 A¹, is a cam C² for controlling the hoisting brake-drum F⁵ by means to be described.

The projecting end of the shaft F carries a small beveled gear-wheel F⁶ in mesh with a beveled pinion J² on a screw-shaft J 10 mounted in lugs A⁴ on the arm A¹ and carrying a movable nut J¹ arranged to travel rearwardly when the shaft F is turned as in hoisting and forwardly during the lowering operation, and to strike the spur E² of 15 the controlling lever E at the limit of the hoisting movement and thus automatically swing the lever and oscillate the shaft C in the direction to cut off the current and apply the jaws D to the motor brake-drum B². 20 The nut J¹ can be located or adjusted to strike the spur E² at any predetermined height of hoist, as governed by the number of turns of the hoisting-shaft F.

Encircling the hoisting brake-drum F⁵ 25 is a brake-band L¹ attached to a brake-lever L extending rearwardly beneath the brake-cam C² on the controlling shaft C. The brake-lever L is raised by a contractile spring L², indicated in dotted lines in Figs. 1 30 and 2, to tighten the brake-band and hold the brake drum F⁵ frictionally, and is forced downwardly to release the brake drum by the action of the cam C². The latter is rounded at the lower front face concentrically 35 to the shaft C so that the rearward movement of the controlling lever E is of no effect on the brake-lever L, but the forward movement of the lever E, toward the load, depresses the brake-lever and releases the 40 hoisting brake-drum F⁵. By manipulating the lever E the operator can control the speed of descent in lowering and stop at any point in such travel.

The operation of the hoisting mechanism 45 is as follows:—Assuming the parts to be in the positions indicated by the full lines in Fig. 1, with the controlling lever E thrown to the rear, the motor brake-drum is released, the motor is operating and the 50 worm B³ is turning the wormwheel G. The hoisting brake-drum F⁵ is held stationary and consequently the beveled gear-wheel F³ is stationary, resulting in the rotation of the shaft F and hoisting drum F¹ in the direction to wind the cable M upon the drum 55 and hoist the load. As the hoisting movement continues the nut J¹ travels rearwardly until the limit of the upward movement of the load is reached, at this point the nut J¹ 60 engages the spur E² on the controlling lever E and forces the latter to the middle position, while still in the grasp of the operator, in which position the current is cut off and the motor brake-drum held, and as in this 65 position the hoisting brake-drum F⁵ is still

held stationary, the differential cannot operate and the load is held suspended.

To lower the load the controlling lever E is swung toward the front and the cam C² thus turned to depress the brake-lever L 70 and release the hoisting brake-drum F⁵. Thus conditioned the worm B³ holds the worm-wheel G stationary, but the gravity of the load turns the hoisting drum in the direction to unwind the cable, and causes 75 the shaft F to rotate with its beveled gear-wheel F², the motion being permitted by the transference of movement through the pinions H² to the beveled gear-wheel F³ and the brake-drum F⁵ fixed thereto. The speed 80 of the lowering operation is varied by manipulating the lever E to induce more or less friction between the brake band L¹ and drum F⁵. It will be noted that during the lowering operation the current is cut off and 85 the motor shaft B¹ held against rotation, thus effecting a saving of electric energy and also permitting the cable to unwind at any desired speed, thus effecting a corresponding saving of time in lowering the 90 load or in engaging the cable M with a succeeding load to be lifted.

I claim:—

1. In a hoisting mechanism, a motor, a motor drive-shaft, a hoisting-shaft, a brake 95 on said hoisting-shaft, differential gearing between said hoisting-shaft and brake, operated by said motor drive-shaft, and controlling means adapted in one position to apply said brake and to actuate said motor 100 to hoist a load, and in another position to stop said motor and release said brake to allow a load to lower by gravity.

2. In a hoisting mechanism, a motor, a motor drive-shaft, a hoisting-shaft, a brake 105 on said hoisting-shaft, differential gearing between said hoisting-shaft and brake, operated by said motor drive-shaft, controlling means adapted in one position to apply said hoisting-shaft brake and to actuate said motor to hoist a load, and in another position to stop said motor and release said brake to allow a load to lower by gravity, and means 110 for automatically changing said controlling means from the hoisting to the lowering position, at a predetermined point in the hoisting movement.

3. In a hoisting mechanism, a motor, a motor drive-shaft, a brake on the latter, a hoisting-shaft, a sleeve on said hoisting-shaft, a brake on said sleeve, differential gearing between said hoisting-shaft and sleeve, operated by said motor drive-shaft, and controlling means adapted in one position to release said motor drive-shaft brake 120 and to actuate said motor to hoist a load, and in another position to stop said motor, apply said motor drive-shaft brake, and release said hoisting-shaft brake to allow a load to lower by gravity, said controlling 125 means

means arranged to control said hoisting-shaft brake and permit the speed of such lowering operation to be varied.

4. In a hoisting mechanism, a motor, a motor drive-shaft, a brake on the latter, a hoisting-shaft, a sleeve on said hoisting-shaft, a brake on said sleeve, differential gearing between said hoisting-shaft and sleeve, operated by said motor drive-shaft, and controlling means adapted in one position to release said motor drive-shaft brake and to actuate said motor to hoist a load, and in another position to stop said motor, apply said motor drive-shaft brake, and release said hoisting-shaft brake to allow a load to lower by gravity, said controlling means arranged to control said hoisting-shaft brake and permit the speed of such lowering operation to be varied, and means for automatically changing said controlling means from the hoisting to the lower position at a predetermined point in the hoisting movement.

5. In a hoisting mechanism, a motor, a motor drive-shaft, a worm on said shaft, an annular worm-wheel in mesh with said worm, a hoisting-shaft, a spider-frame on the latter having its arms engaged in said worm-wheel, beveled pinions on said arms, a sleeve on said hoisting-shaft, a beveled gear-wheel fixed on said hoisting-shaft and in mesh with said pinions, a beveled gear-wheel fixed on said sleeve and in mesh with said pinions, a hoisting drum on said hoisting-shaft, a brake drum on said sleeve, and means for holding said worm and said brake drum against rotation.

6. In a hoisting mechanism, a motor, a motor drive-shaft, a worm on said shaft, a hoisting-shaft, a worm-wheel in mesh with said worm, a spider-frame loosely mounted on said hoisting-shaft and having its arms engaged in said worm-wheel, beveled pinions on said arms, a sleeve loosely inclosing said hoisting-shaft, a beveled gear-wheel fixed on said hoisting-shaft and in mesh with said pinions, a beveled gear-wheel fixed on said sleeve and in mesh with said pinions, a hoisting-drum on said hoisting-shaft, a brake drum on said sleeve, a brake-band on said brake drum, a spring actuated brake-lever arranged to actuate said band and hold said brake drum, and a controlling shaft

having a cam for moving said brake-lever in opposition to its spring and relaxing said band.

7. In a hoisting mechanism, a motor, a motor drive-shaft, a brake thereon and a worm on said shaft, a hoisting-shaft, a worm-wheel in mesh with said worm, a spider-frame loosely mounted on said hoisting-shaft and having its arms engaged in said worm-wheel, beveled pinions on said arms, a sleeve loosely inclosing said hoisting-shaft, a beveled gear-wheel fixed on said hoisting-shaft and in mesh with said pinions, a beveled gear-wheel fixed on said sleeve and in mesh with said pinions, a hoisting drum on said hoisting-shaft, a brake drum on said sleeve, a brake-band on said brake drum, a spring actuated lever arranged to actuate said band and hold said brake drum, a controlling shaft having a cam for moving said brake-lever in opposition to its spring and relaxing said band, and means actuated by said controlling shaft for applying said drive-shaft brake.

8. In a hoisting mechanism, a motor, a motor drive-shaft, a brake and a worm on said shaft, a hoisting-shaft, a worm-wheel in mesh with said worm, a spider-frame loosely mounted on said hoisting-shaft and having its arms engaged in said worm-wheel, beveled pinions on said arms, a sleeve loosely inclosing said hoisting-shaft, a beveled gear-wheel fixed on said hoisting-shaft and in mesh with said pinions, a beveled gear-wheel fixed on said sleeve and in mesh with said pinions, a hoisting drum on said hoisting-shaft, a brake drum on said sleeve, a brake-band on said brake drum, a spring actuated brake-lever arranged to actuate said band and hold said brake drum, a controlling shaft having a cam for moving said brake-lever in opposition to its spring and relaxing said band, means actuated by said controlling shaft for applying said drive-shaft brake, a controlling lever on said controlling shaft, a spur on said lever, a screw-shaft rotated by said hoisting-shaft, and a traveling nut on said screw-shaft, arranged to strike said spur and move said controlling-lever and controlling-shaft.

In testimony that I claim the invention above set forth I affix my signature.

JOSEPH H. DONAT.
